UNITED STATES PATENT OFFICE.

CHARLES F. BRYAN, OF HETLAND, SOUTH DAKOTA.

SNOWPLOW.

Application filed May 22, 1924. Serial No. 715,207.

To all whom it may concern:

Be it known that I, CHARLES F. BRYAN, a citizen of the United States, residing at Hetland, in the county of Kingsbury and State of South Dakota, have invented certain new and useful Improvements in a Snowplow, of which the following is a specification.

This invention relates to new and useful improvements in snow plows and has for its principal object to provide a simple and efficient means for removing snow from a road or highway, means being associated therewith for discharging the snow removed from the road to the side thereof.

A further object of the invention is to provide a snow plow of the above mentioned character, wherein means is provided for breaking up the lumps of snow before the same reaches the blower fan whereby the same may properly receive and discharge the snow in such a manner as to prevent the clogging of the snow plow.

A still further object of the invention is to provide a snow plow of the above mentioned character, which is of such a construction as to enable the same to be readily attached to a tractor for operating the same, means being provided for actuating the rotary cutter and blower fan of the plow simultaneously.

A further object is to provide a snow plow of the above mentioned character, which is simple in construction, inexpensive, strong and durable and furthermore adapted for the purposes for which it is designated.

Other objects and advantages of this invention will become apparent during the course of the following description.

In the accompanying drawings forming part of this specification and in which like numerals designate like parts throughout the same:

Figure 1 is a side elevation of my improved snow plow.

Figure 2 is a rear elevation thereof.

Figure 3 is a front elevation thereof, and

Figure 4 is a vertical section showing the arrangement of the rotary cutter and blower fan.

In the drawings wherein for the purpose of illustration is shown the preferred embodiment of my invention, the numeral 1 designates a substantially rectangular shaped casing, the front face of which is

open. Arranged on the lower edge of the forward portion of the casing is the scoop 2, the purpose of which is well known in the art. Extending centrally through the casing is the driven shaft 3 on the forward end of which is supported and adapted to rotate therewith, the rotary cutter designated generally by the numeral 4.

The rotary cutter comprises the enlarged annular rim 5 and the hub portion 6 which is mounted on the outer forward end of the shaft 3. Cutter blades such as are illustrated at 7 extend radially between the hub portion 6 and the rim 5 in the manner more clearly illustrated in Figure 3 of the drawings. Suitable bracing means such as illustrated at 8 extend from the annular rim to a sleeve 9 which is secured on the shaft 3 at a point adjacent the hub portion 6 in the rotary cutter 4 in the manner more clearly illustrated in Figure 4 of the drawings. The cutter is adapted to rotate within the casing 1 in such a manner as to break up the lumps of snow which are delivered to the cutter by the scoop 2 as the snow plow moves along the road or highway.

The bottom of the casing is inclined rearwardly as illustrated at 10 to provide the accumulation and depositing of the snow therein. Communicating with the back of the casing adjacent the lower central portion thereof is the fan casing 11. Extending through the casing 11 is the shaft 12 and mounted on the forward end thereof and arranged within the fan casing 11 is the blower fan 13 which is adapted to rotate with the shaft in the manner herein-after to be more fully described.

The fan or blower casing 11 is provided with an outlet pipe 14 which extends upwardly therefrom adjacent the rear portion of the casing 1 and a discharge pipe such as illustrated at 15 is movably supported on the upper end of the outlet pipe 14, a supporting collar such as illustrated at 16 being provided for enabling the discharge pipe to be rotatably supported on the outlet pipe whereby the former may be moved in any desired position. The provision of the outlet and discharge pipe provides a means whereby the snow will be delivered therethrough by the rotary fan and will cause the snow to be discharged along the side of the road or highway when the snow plow is in use.

The outer end of the shaft 3 is supported by means of a suitable bracket illustrated at 17 which extends upwardly from the rear portion of the fan casing 11. The shaft 12 has its rear end supported in a suitable bracket 18 which is also mounted on the rear portion of the fan casing 11 in the manner more clearly illustrated in Figures 1 and 2 of the drawings. Suitable bearings such as 10 are illustrated at 19 and 20 respectively are secured to the rear portions of the casing and fan casing 11 for cooperation with the shafts 3 and 12 respectively which extend therethrough. Grease cups such as are 15 shown at 21 are provided for each of the bearings for the purposes well known in the art.

Journaled in suitable brackets 22 and 23 respectively which are supported by the fan 20 casing 11 and extending transversely to the shaft 3 is the shaft 24. One end of the shaft 24 is provided the pulley wheel 25 which is adapted to be driven by any suitable source of power from the tractor upon 25 which the snow plow is mounted and on the opposite end of the shaft 24 is provided a beveled gear 26. This beveled gear is adapted to mesh with a beveled gear 27 mounted on the rear end of the shaft 3 whereby the 30 latter may be driven for rotating the rotary cutter 4 arranged on the forward end thereof and disposed within the casing 1. For the purpose of simultaneously rotating the fan 13, I provide the shafts 3 and 12 respectively with aligning sprocket wheels 28 and 29 respectively and over which is trained the sprocket chain 30. It will thus be seen that when the shaft 24 is actuated through the medium of the pulley 25, the shafts 3 and 12 respectively will be simultaneously 40 operated for actuating the rotary cutter and rotary fan.

The operation of my improved snow plow may be briefly stated as follows: The plow 45 is adapted to be supported on the forward end of a tractor in any suitable manner and the belt pulley wheel 25 is connected to the power plant of the tractor by any suitable means. As the tractor with the snow plow 50 thereon moves along the surface of the road or highway, the scoop 2 will cause the snow on the road to be delivered to the casing 1 where the rotary cutter will break the lumps and deliver the snow to the inclined bottom 55 10. The rotary fan 13 will by suction cause the snow within the bottom of the casing 1 to be drawn through the opening 31 provided in the rear portion of the casing discharged outwardly through the outlet 14 60 and discharge pipe 15 to the side of the road.

The simplicity of my snow plow enables

the same to be easily and readily placed in an operative position and when in use will efficiently remove the snow from a road or highway. A snow plow of the above mentioned character, may be manufactured at a very low cost and will further be strong and durable.

While I have shown the preferred embodiment of my invention, it is to be understood that various changes in the size, shape and arrangement of parts may be resorted to without departing from the spirit of the invention and the scope of the appended claims.

Having thus described the invention, what I claim is:—

1. A snow plow comprising a casing, a scoop provided on the lower forward edge thereof, the front face of the casing being open, a shaft extending centrally through the casing, a rotary cutter supported on the forward end of the shaft and disposed within the casing, a fan casing arranged on the rear portion of the aforementioned casing and communicating with the lower portion thereof, a shaft extending through the fan casing, a rotary fan supported thereon and disposed within the fan casing, brackets on said fan casing for supporting said shafts, a beveled gear mounted on the rotary cutter shaft, a drive shaft supported on the fan casing, means associated with one end of the drive shaft for operating the same, a beveled gear on the opposite end of the shaft for cooperation with the beveled gear on the rotary cutter shaft, aligning sprocket wheels provided on the rotary cutter shaft and the fan shaft, a sprocket chain extending over the sprocket wheels whereby the rotary fan and rotary cutter are actuated simultaneously, and an outlet pipe extending upwardly from the fan casing.

2. A snow plow comprising a substantially rectangular casing open at its front, a scoop on the lower forward edge thereof, the bottom of the casing being inclined rearwardly, a shaft extending centrally through the casing, a rotary cutter mounted on the forward end of the shaft and disposed within the casing, a fan casing arranged on the rear portion of the aforementioned casing and communicating with the lower portion thereof, a shaft extending through the fan casing, a rotary fan supported thereon and disposed within the fan casing, means for rotating the shaft simultaneously, and an outlet pipe extending from the fan casing.

In testimony whereof I affix my signature.

CHARLES F. BRYAN.
